UNITED STATES PATENT OFFICE.

STERLING F. HAYWARD, OF NEW YORK, N. Y.

DESIGN FOR A BOTTLE.

SPECIFICATION forming part of Design No. 16,562, dated March 9, 1886.

Application filed September 22, 1885. Serial No. 158,486. Term of patent 12 years.

To all whom it may concern:

Be it known that I, STERLING F. HAYWARD, a citizen of the United States, residing at New York city, in the county of New York and State of New York, have invented and produced a new and original Design for a Bottle, of which the following is a full, clear, and exact description, reference being had to the accompanying drawing, forming part thereof, in which I have shown a perspective view of my newly-designed bottle.

My design for bottles consists in panels of diamond shape, sunk or depressed below the main surface of the quartered and truncated spherical body of the bottle.

Broadly considered, it is not original with me to provide a bottle with sunken panels or to make diamond-shaped panels on bottles, and I lay no claim thereto.

In my design the bottle *b*, of essentially the shape shown, is provided with panels *a*, of diamond shape, sunk or depressed below the contiguous surface of the bottle. The body

of the bottle is a truncated sphere, quartered by vertical depressions *c*, and a sunken panel *a* is put in each quarter. The neck rises from a pedestal or collar, *e*, of less diameter than the truncated top of the body.

What I claim is—

1. The design for a bottle, comprising the diamond-shaped sunken panel *a* on a truncated spherical quartered body, as shown and described.

2. The design for a bottle, consisting of a series of diamond-shaped panels, *a*, sunk or depressed below the contiguous surface, the truncated spherical quartered body, and the neck, as shown and described.

In testimony whereof I have hereunto set my hand this 12th day of September, A. D. 1885.

STERLING F. HAYWARD.
